CORN CUTTER

Robert Gamble Cabell, III, Richmond, Va.

Application November 18, 1943, Serial No. 510,804

9 Claims. (Cl. 30—276)

This invention relates to cutters adapted to be attached to the leg of a worker and actuated by the shifting of the worker's weight from one foot to the other as he walks along. It is intended primarily for use in cutting standing corn stalks.

Standing corn is usually cut with a knife, the farmer proceeding along the row, bending over as he comes to each stalk and severing the stalk a short distance above the ground. The cut stalk is dropped and the farmer continues down the row. Later his steps must be retraced to pick up the cut stalks and set them up in shocks. He cannot gather the stalks as he goes along, for he must use his hands to handle the cutting knife. This necessitates going over the same field twice, or the use of two men—one to cut and the other to shock.

The object of the present invention is to provide a cutter having means whereby it may be attached to the leg of a farmer and the cutting blade set in motion as the farmer walks so that the farmer will have both hands free to gather the stalks as they are cut and the necessity for stooping or bending is eliminated.

It is also an object to provide a device of this character in which the operation of the cutting blade is under the full control of the user, it merely being necessary that the user's weight be shifted to the leg to which the device is attached to actuate the knife regardless of whether a circular knife and a rotating motion, or a linear blade and an oscillating motion, is employed. It is further contemplated that the knife be guarded to protect the free leg of the user as he walks along.

Another object of the invention is to provide means to delay the action of the knife and build up the actuating power to be suddenly released, thereby quickening the cutting stroke as the knife strikes the stalk.

Other objects will become apparent from the following description taken in conjunction with the drawings which accompany and form a part of this specification and through the several figures of which like characters of reference are used to denote identical parts.

In the drawings:

Figure 1 is a perspective view of a cutter embodying the principles of the present invention;

Figure 2 is a sectional view on the line 2—2 of Figure 1, looking at the underside of the cutting blade and the leg attaching means;

Figure 3 is a side elevation of the cutter, parts being broken away in section;

Figure 4 is a vertical section taken on the line 4—4 of Figure 3;

Figure 5 is a modified form of the invention showing the cutter adapted for use with a linear cutting blade;

Figure 6 is a section taken on the line 6—6 of Figure 5;

Figure 7 is a side elevation of the cutter shown in Figure 5.

Referring to the drawings in detail and first advertizing to that form of the invention shown in Figures 1 to 4, inclusive, the cutter comprises a frame 1 to which is journaled a rotary cutting blade 2. The frame 1 has a pair of rearwardly extending arms 3 and 4, rigidly connected at their ends as at 5 to a band 6 adapted to encircle the leg of the person using the cutter. The band 6 is split and provided with straps 7 so that the bands may be opened to fit about the leg 15 and then buckled tightly in position.

The arms 3 and 4 of the frame are arranged in a horizontal plane, and curve forwardly and join at a point removed from the leg band 6. From their point of juncture, arms 8 and 9 emerge 20 and extend forwardly, terminating in bosses 10 and 11 which provide bearings for the cutter blade shaft 12. The arms 8 and 9 are arranged one above the other so as to hold the cutter shaft in a vertical position and to position the cutter blade horizontally. A guard 13 is attached to one of the arms 3 or 4, depending upon whether the device is to be worn upon the right or left leg, and extends outwardly and around a portion of the cutter blade.

To impart rotation to the cutter blade, there is provided a bellows-like unit 14 having on its upper side a heel-fitting depression 15 to slip over the heel and attach the unit to the shoe of the user. At the bottom of the unit there is a ground-contacting member 16, and the members 15 and 16 are separated by a coil spring 17, the two members being joined by a flexible housing 18 surrounding the spring. A bell crank lever 19 is attached to the leg band 6 as at 20 and has its lower arm 21 connected to the ground-contacting member of the unit 14 by means of the rod 22. The arm 21 is preferably shorter than the arm 23 of the lever to provide for maximum actuating movement for the cutter, with minimum movement between the members of the unit 14. The arm 23 carries an actuating rod 24 which is composed of two parts, 25 and 26, the part 25 telescopically sliding within the part 26. The sleeve portion 26 of the actuating rod 24 is provided 35 with slots 27, and the rod 25 has a pin 28 passing through its outer end and extending outwardly for sliding engagement with the slots 27.

Sleeve 26 is pivotally connected to one side of a substantially triangular rocking lever 29, the lever 29 being pivoted as at 30 to a bridge piece 31 extending between the arms 3 and 4. A second actuating rod 32 is pivotally connected to the opposite side of the lever 29. The rod 32 is journaled as at 33 to permit rectilinear 45 movement of the rod as the lever 29 rocks about

its pivot. It is necessary that a slotted connection be provided between the rod 32 and the lever 29 as is shown at 34. The extreme end of the rod 32 is made in the form of a toothed rack 35 to operatively engage a pinion 36 fixed to the lower end of the cutting blade shaft 12. A spring 37 has one end attached to the outer portion of the lever 29, as at 38, and its other end anchored to the bridge piece 31, as at 39. It will be noted that the spring is offset with respect to the pivot 30 of the lever 29 so as to normally hold the lever in the position shown.

After the device has been attached to the leg of a farmer, or other worker, the cutting blade will be actuated each time the farmer's weight is put upon the leg carrying the device. As he steps down upon this foot, the unit 14 will collapse, moving the rod 22 upward and rotating the bell crank lever about its pivot. Movement of the bell crank lever will move the portion 25 of the actuating rod 24 forward and as the pin 28 is in contact with the end of the slots 27 in the member 26, the member 26 will also move, rocking the lever 29 about its pivot. The second actuating lever 32 will also move, causing rotation of the pinion 36 and the cutting blade 2. This movement is sufficient to carry the spring 27 over the pivot 30 of the lever 29, whereupon the spring will act to draw the lever 29 downward, moving the portion 26 of the actuating rod 24 on the portion 25 until the pin 28 strikes the opposite end of the slots 27. This second phase of movement will be greatly accelerated over the first, increasing the speed of the knife as it strikes the stalk to make a clean cut.

When the farmer lifts his weight from the leg carrying the cutter, the spring 17 will expand, drawing down the rod 22 and returning the bell crank 19 to its inoperative position. As the pin 28 was in contact with the end of the slot nearest the bell crank lever at the beginning of this return stroke, the lever 29 will be rocked until the spring 37 has again passed over the pivot 30, whereupon the spring will snap the lever to its inoperative position with the pin 28 abutting the end of the slots 27 furthest removed from the bell crank lever.

Now advertizing to that form of the invention shown in Figures 5 to 7, inclusive, the circular cutting blade of the first form has been replaced by a linear blade 40. The unit 14, leg-encircling band 6, arms 3 and 4 of the supporting frame, bridge piece 31, lever 29, and interconnecting operating mechanism is identical to that employed in the first form. However, the arms 8 and 9 of the frame in the first form are eliminated and the pivot for knife 40, indicated at 41, is provided at the juncture of the arms 3 and 4. Knife 40 has an arm 42 extending at right angles to the knife blade, the outer end of which is pivotally connected to lever 29 by means of link 43. It can readily be seen that this form of the invention operates in substantially the same manner as that form previously described except that the knife has an oscillating motion swinging in a counterclockwise direction in its cutting stroke. The snap action provided by spring 37 and lever 29 is perhaps of greater value in this form of the invention than in the first form, as the knife is swung slowly to the stalk and as it approaches the stalk its momentum is suddenly increased to provide a quick cutting stroke.

In the use of this invention in either of the illustrated forms, a farmer may walk along a row of standing corn and so gauge the length of his stride that each time his weight is put upon the leg carrying the cutter, that leg will be in proper position for the knife blade to cut a stalk. As his arms are free, he may gather the stalks as cut without the necessity for banding and stooping.

10 Various modifications in the precise structure and arrangement of parts will readily suggest themselves to those skilled in the art, but within the scope of the present invention, as claimed.

Having thus described my invention, I claim:

15 1. A cutter comprising, a frame, means to attach the frame to the leg of a worker, a knife blade pivoted to the frame, and means to impart motion to said knife when the weight of the worker is shifted to the leg to which the cutter is attached.

20 2. A cutter comprising, a frame, means to attach the frame to the leg of a worker, a knife blade pivoted to the frame, a collapsible member to fit under the shoe of the worker, and linkage connecting said collapsible member and said knife blade whereby the knife blade will be moved when the weight of the worker is shifted to the leg to which the cutter is attached.

25 3. A cutter comprising, a frame, means to at-

30 tach the frame to the leg of a worker, a knife blade pivoted to the frame, a collapsible member to fit under the shoe of the worker, linkage connecting said collapsible member and said knife blade whereby the knife blade will be moved when the weight of the worker is shifted to the leg to which the cutter is attached, and means interposed in said linkage whereby the movement of said knife blade will be accelerated after its initial movement.

35 4. A cutter as claimed in claim 3 wherein the accelerating means comprises a lever and a spring to cause said lever to snap over dead center position.

40 5. A cutter comprising, a frame, means to attach said frame to the leg of a worker, a circular knife blade pivoted to the frame, a collapsible member to fit under the shoe of the worker, and linkage connecting said collapsible member and said knife blade whereby the knife blade will be rotated when the weight of the worker is shifted to the leg to which the cutter is attached.

45 6. A cutter as claimed in claim 5, said knife blade carrying a pinion and said linkage terminating in a rack bar.

50 7. A cutter comprising, a frame, means to attach said frame to the leg of a worker, a linear knife blade pivoted to the frame, a collapsible member to fit under the shoe of the worker, and linkage connecting said collapsible member and said knife blade whereby the knife blade will be oscillated when the weight of the worker is shifted to the leg to which the cutter is attached.

55 8. A cutter as claimed in claim 7, said knife blade carrying a lever arm connected to said linkage.

60 9. A cutter as claimed in claim 2, means incorporated in said collapsible member to return the linkage to its inoperative position.
